MOTOR HOME

Marvin E. Nerem, Forest City, Iowa, assignor to Winnebago Industries, Inc., Forest City, Iowa, a corporation of Iowa

Filed June 26, 1967, Ser. No. 7,597

Term of patent 14 years

(Cl. D14—3)

I claim:

The ornamental design for a motor home, substantially as shown.
